CLAIM

The ornamental design for a combined telephone set
and base therefore, as shown.

DESCRIPTION

FIG. 1 is a perspective view of a combined telephone
set and base therefore, showing our new design;

FIG. 2 is a side elevation thereof, of an enlarged scale,
the opposite side being a mirror image of the side
shown;

FIG. 3 is a rear elevation thereof, of an enlarged scale;
and

FIG. 4 is a front elevation thereof, of an enlarged scale.

FIG. 1

FIG. 2

FIG. 3
